CLAIM

The ornamental design for a telepresence display, as shown.

DESCRIPTION

FIG. 1 is a perspective view of the telepresence display showing our new design in relation with telepresence equipment; and,

FIG. 2 is an overhead view thereof.

The FIGURES are shown with the telepresence display as used in the environment. Broken lines are directed to environment and are for illustrative purposes only.

1 Claim, 2 Drawing Sheets

FIG. 1

FIG. 2
